UNITED STATES PATENT OFFICE

FREDRECK C. HUONKER, OF DAYTON, OHIO

ADJUSTABLE STAND AND RACK

Application filed November 27, 1928. Serial No. 322,278.

This invention relates to adjustable stands and racks of the type intended to be attached to beds, chairs, and the like, to facilitate reading from books, magazines, newspapers and the like and obviating the necessity of holding such articles in the hand as is ordinarily done.

The invention is more especially intended for use upon hospital beds to facilitate reading by the patient while in an inclined or sitting posture.

The principal novelty is predicated upon an invention which embodies a number of desirable features, associated and cooperating in a manner to insure the desired compactness and convenience, and to permit the use of superior adjustment in order that clear vision may be had by the reader while assuming different permissible and convenient positions.

It is also an object to provide a new contribution to the art, which is characterized principally by a distinctive attaching device, and a foldable support which is adjustable in numerous directions for arranging the reading matter to the best advantage of the reader, to allow the support to be swung down to an out-of-the-way position, when not in use.

Other features and advantages of the invention will become more readily apparent from the following description and drawings.

In the drawings:

Figure 1 is an elevational view, partly in section of a complete stand and rack constructed in accordance with the present invention.

Fig. 2 is an enlarged end view of the slideable rack seen in Fig. 1, looking in the direction from right to left.

Fig. 3 is an enlarged end view of the structure seen in Fig. 1, looking in a direction from left to right.

Fig. 4 is an elevational view of the clamp.

Fig. 5 is a sectional view through the clamp taken approximately upon the plane of the line 5-5 of Fig. 4.

Fig. 6 is an exaggerated sectional view taken on the line 6-6 of Fig. 1.

Fig. 7 is a longitudinal section through a portion of the mounting for the pivoted rack.

Fig. 8 is a cross sectional view through the structure seen in Fig. 7.

Fig. 9 is a cross section on the line 9-9 of Fig. 1.

Fig. 10 is a sectional and elevational view of a modification.

Fig. 11 is a horizontal section through the structure seen in Fig. 10, observing the details of the base.

Referring now to the drawings by reference numerals, it will be observed that one of the principal parts of the invention is the novel fixture or device 12 employed for attachment to a bed, chair or the like. This comprises a special casting including a clamp having an upper rigid jaw 13, and an adjustable jaw 14 operated thru a flange 15, by way of an actuating screw 16.

As seen in Figs. 3, 4 and 5, the plate or web portion 17 is provided with a pivoted coupling 18. On the same side of the plate is an arcuate outstanding flange 19 having a central opening forming a keeper hole at 20, and having seat forming notches 21 at its opposite end.

The stand which cooperates with this device 12, comprises a vertical standard 22 whose lower end portion extends through an opening in the coupling 18. The reduced terminal 23 on the lower end is normally receivable in the keeper opening 20 as shown in Fig. 3, when the device is set up for use.

Beneath the coupling 18, is a stop flange 24, which allows the standard to be lifted up and slid through the opening in the coupling 18 a slight distance, in order to withdraw the reduced end 23 from the keeper hole 20. Then the standard can be swung on the vertical pivot formed by the coupling, from a vertical position to a lowered position as shown in dotted lines in Fig. 3.

With this arrangement, the standard is allowed to swivel on a vertical axis, while in a vertical position, or is allowed to be lifted up and swung down to the horizontal folded position. Thus coupling 18 provides a two-way connection of an advantageous type.

Fastening through the medium of a bracket 25 to the upper end of the standard as seen in Fig. 1, is a supporting arm 26 for the adjustable rack 27. This rack is obviously constructed to support books, magazines, newspapers, and other reading matter.

The rack comprises a series of links 28 and 29 connected together and in turn connected with a right angularly horizontally disposed article supporting ledge 30. Mounted upon the central portion of this ledge is a spring-actuated article retaining clip 31. The links 29 are pivoted to a connecting strip 32, which is rigidly fastened to a tapered connecting block 33 as shown in Fig. 8. This block is pivotally connected by a screw 34 to an adjusting slide 35. With this arrangement, the rack is maintained in a proper inclined position, and is allowed to be adjusted to obtain the best suitable position for the different positions which the user assumes from time to time, while reading.

Attached to the slide as shown in Fig. 7, is the bracket 36 carrying a spring-pressed latch or retaining pin 37. Also carried by the link 28 and centrally arranged is an additional clip or clasp 38, cooperating with the clip 31 to aid in holding the article on the rack. In Fig. 1, the reference numeral 39 designates a connecting link and brace. The upper end of this, is pivoted to the arms 26 while the lower end is pivotally connected to a sliding sleeve 40.

This sleeve 40 is slidable along the standard and held in different adjusted positions by a pivoted retainer 41. The reference character 42 designates a resilient hook which aids in holding the structure in a collapsed position when the arms 26 are swung down against the standard 22.

With this arrangement it is obvious that the arm 26 can be adjusted to the desired angle with respect to the standard. Moreover, an individual adjustment or adjustments of the rack, 27 may be had, and the reading matter can be clamped on the rack for security. Then, the complete unit comprising the standard 22, the arm 26 and the rack 27, can be swung toward and from the user.

For instance, it can be swung over the bed or away from the bed. This is permitted by the turning of the standard 22 in the coupling 18 and the keeper hole 20 as is obvious from Fig. 3. Moreover, as before stated, when it is desired to swing the device down alongside of the bed to dispose it out of the way, the standard is simply lifted to withdraw the end 23 from the keeper hole 21, and then the standard is disposed in the horizontal position shown in dotted lines, at which time it rests in the seats 21 seen in Fig. 1.

In instances where it is not desired to fasten the stand to a bed or chair through the medium of the device 12, and when it is

desired instead to support the standard from the floor, I provide an arrangement such as seen in Figs. 10 and 11.

Referring to the last figures, it will be seen that 43 designates a hollow base having vertically alined bearings 44 and 45 in which the standard 46 is journaled for rotation. A stop collar 47 is provided to insure relation of parts. Moreover, I provide a counter-weight 48 connected to the standard through the medium of an attaching portion 49. The parts 48 and 49 are located within the base and concealed from view. However they are important in holding the standard in different positions in which it is turned from time to time while being used.

The weight in fact, facilitates such turning because of its counter-balancing action. It is believed that by considering the description in connection with the drawings, a clear understanding of the invention, operation, features and advantages of the invention will be had. Consequently, a more lengthy description is regarded unnecessary.

Minor changes in shape, size, and re-arrangement of parts, coming within the field of invention claimed may be resorted to in actual practice if desired.

Having thus described my invention, what I claim as new is:

In an adjustable stand and rack structure of the class described, a standard, and supporting means for said standard comprising a hollow flat bottom base provided with vertically alined bearings, said standard being rotatable in said bearings, and a counter-weight in said base attached to said standard.

In testimony whereof I affix my signature.

FREDRECK C. HUONKER.
